HIGH FREQUENCY IGNITION SYSTEM

Samuel Ruben, New Rochelle, N. Y.

Application June 13, 1942, Serial No. 446,853

4 Claims. (Cl. 315—177)

This invention relates to ignition systems for internal combustion engines.

An object of the invention is to improve high voltage ignition systems.

Another object is to improve high altitude ignition systems, such as are used in aircraft, and to reduce or eliminate the ignition difficulties frequently encountered at high altitudes such as corona discharge and electric breakdown of the system.

A further object is to improve the operation of ignition systems under various conditions of spark plug fouling.

Other objects of the invention will be apparent from the following description and accompanying drawing taken in connection with the appended claims.

This application is a continuation-in-part of my prior filed co-pending application, Serial No. 437,322, filed April 2, 1942.

The invention comprises the features of construction, combination of elements, arrangement of parts, and methods of manufacture and operation referred to above or which will be brought out and exemplified in the disclosure hereinafter set forth, including the illustrations in the drawing.

In the drawing:

Figure 1 is a circuit diagram of an ignition system for an internal combustion engine embodying features of my invention;

Figures 2 and 3 illustrate modifications of part of the ignition circuit;

Figure 4 illustrates a temperature compensating feature applied to the ignition circuit;

Figure 5 is a diagram showing the preferred arrangement of the parts of the ignition circuit;

Figure 6 shows the construction of a condenser used in the circuit;

Figure 7 shows a temperature compensating auxiliary condenser which may be used in the circuit;

Figures 8 and 9 are top section and side views, respectively, of a spark gap;

Figure 10 is a section through an induction coil used in the circuit; and

Figure 11 is an end view thereof.

The present invention relates to an improvement and simplification of ignition systems of the type described in my prior filed co-pending application mentioned above. In its preferred form it embodies the use of a low tension magneto for energizing a spark gap and utilizes a high frequency auto-transformer for applying the oscillations in the spark gap circuit to the

ignition distributor circuits leading to the various spark plugs. The system is of lighter weight and less parts than the prior system.

One of the principal limitations on high altitude flying has been the difficulty of providing ignition systems for airplane engines which are not subject to electric breakdown due to the rarification of the air at high altitudes. The low atmospheric pressure at these altitudes permits corona discharges to develop between points of high potential difference. In high tension magneto systems the magneto may practically cease to function at times due to flash-over in the magneto itself. The high tension cables in the distributor manifold and leading from the magneto to the manifold also break down unless shielded in the proper type of cables. The distributor is also subject to arc-over and disruption of proper timing at high altitudes.

20 The system of the present invention produces an ignition voltage of high frequency and steep wave front so as to effect sparking of the plugs even under conditions of adverse plug fouling.

The system also does away with the necessity for a distributor of the type using a spark gap between the rotating contact and the stationary terminals and enables the substitution of a direct contact type of distributor. The distributor is not required to make and break any substantial current, however, as the spark voltage is generated only when the distributor is in the middle of its contact position with any of the stationary terminals.

The system also allows the use of larger sizes of spark plugs for all operating conditions, thus improving the maximum power development of the engine during take-off and other periods of peak performance requirements.

In the past where high frequency systems have been used they have depended upon the use of a high frequency transformer to apply the voltage to the spark plug. This required a fairly high voltage transmission to the primary to avoid excessive or impractical transformer ratios and, unless the transformer was close to the plug, insulation and distributed capacity losses were substantial. In the present system a high potential is developed across the spark plug electrodes by use of a resonant circuit. However, due to the arrangement of the resonant circuit elements in relation to the high frequency energy source and the spark plugs, the main part of the circuit is operated at low voltage. Thus the voltage on the distributor and in the manifold is kept at a low value, such as 1,500 volts, where arc-over or break-

down of the insulation at high altitudes does not take place.

Referring to the drawing the ignition system shown in Figure 1 comprises a low tension magneto 12 preferably of the inductor type for producing periodic discharges across a spark gap 13 connected in an oscillatory circuit comprising a condenser 14 and an inductance 15. The high frequency oscillations in this circuit are distributed by distributor 16 to the various spark plug circuits in sequence such as circuit 17 containing series condenser 18 and an inductance 19 which is connected in shunt with the electrodes of spark plug 20.

The magneto may be of well known type comprising a permanent magnet which rotates past the poles of a stationary core 26 upon which the primary and secondary magneto windings 27 and 28 are wound. The magneto mechanism includes a rotating cam 21 geared to the engine, the gear ratio and the number of cam points being related to close and open cooperating contacts 22 each time a spark is required at one of the spark plugs. Upon each opening of contacts 22 the primary current is interrupted causing a sudden collapse in flux which induces a voltage impulse across magneto secondary 28 which charges condenser 14 through low impedance coil 15 to a voltage sufficient to produce a breakdown of gap 13. Breakdown of the spark gap produces high frequency oscillations in the oscillatory circuit comprising condenser 14 and inductance 15. The oscillatory voltage developed across inductance 15 is of comparatively low value, for example about 1,500 volts peak.

Rotating arm 23 of distributor 16 is driven by the engine at such speed as to connect one of the spark plug circuits 17 each time a spark is required at its associated plug. Accordingly, at the instant when a magneto impulse is produced by the action of cam 21 resulting in breakdown of spark gap 13 and high frequency oscillations in the oscillatory circuit, the pinion gear contact 24 on the end of distributor arm 23 is in positive contact with one of the segments 25 of the stationary part of the distributor, which segment is connected to one of the spark plug circuits 17. A wiper contact may be used in the distributor in place of the pinion gear, if desired.

The low voltage oscillations of high frequency developed across inductance 15 is thus applied to the individual spark plug circuits in sequence. The series condenser 18 and the inductance 19 individual to each of these circuits, when connected by the distributor to the end of inductance 15, form with it a resonant circuit which is tuned to resonate at the frequency of the oscillations generated in the oscillatory circuit, associated with the spark gap. These oscillations result in the creation of a high oscillatory voltage across inductance 19 and hence across the electrodes of spark plug 20 producing a spark thereat. However, the peak voltage developed at the distributor and in line 17 remains comparatively low, such as about 1,500 volts, due to the phase relations in the circuit. The peak voltage developed across each of the resonance circuit components is 10,000 to 15,000 volts dependent upon the efficiency of those elements.

Figure 2 illustrates a modification of the circuit in which the inductance 19 is connected in series with line 17 leading to the spark plug and capacitance 18 is connected across the spark plug electrodes. With this circuit the energy of the spark discharge per oscillation is somewhat greater.

Whether the circuit of Figure 1 or that of Figure 2 is used will depend in part upon the permissible amount of spark plug wear or erosion.

It is also possible to utilize a step-up transformer in connection with the resonant circuit as shown, for example, in Figure 3, wherein the primary 30 of a high frequency transformer is connected in series with condenser 18 and the secondary 31 is connected in shunt with the spark plug electrodes. The transformer may, in some cases, be in the form of a step-up autotransformer.

When the ignition system is exposed to wide variations in temperature, such as from -40° C. to +40° C., changes in the dielectric constant of the cable and the other parts of the system will affect the resonant frequency of the oscillatory circuits. The circuit elements may be designed and constructed to minimize or compensate for this effect. For instance, condensers may be used having dielectrics whose dielectric constant varies with temperature in such a manner as to maintain the resonance condition of the circuits. Thermostatic control means may also be used.

Figure 4 illustrates one type of thermostatic compensation which comprises a flat universal wound inductance coil 35, mounted on base 38 and connected in series with the oscillatory spark gap circuit and having a powdered iron core element 36 supported on a thermostatic bi-metal element 37 for varying the inductance of the coil with variation in temperature conditions to maintain the optimum resonance conditions. Figure 4 also illustrates that inductance 15 which is, in effect an auto-transformer, can be connected as a step-up (or step-down) transformer.

Figure 5 illustrates a suitable arrangement for the parts of the ignition circuit. The casing 40 contains the magneto, the spark gap, the oscillation coil and condenser and the distributor, shaft 41 being driven by the engine. The segments 25 of the distributor are connected to the conductors of the cable manifold which may be shielded in a well-known manner. Condensers 18 may be connected in series with the conductors of the cable manifold near the spark plugs and inductance coils 19 may be enclosed in copper sheaths and mounted on or made part of the spark plugs themselves, or also be mounted in the manifold. In some cases the coils 19 may be inserted inside the glass tube comprising condensers 18.

Condenser 18 may be constructed as illustrated in Figure 6 of a Pyrex glass tube 50 having inside 55 and outside conductive coatings 51 and 52 which form the condenser electrodes. The coatings may be made by grinding precipitated silver with about 7% polystyrene and forming a varnish with xylol as a solvent. This is painted on the tube leaving wide margins at the tube ends. The coating is then baked and then electroplated with a thin layer of copper to insure continuity and strength. In order to reduce edge effects, a pair of cupped metal rings 53 are inserted inside the tube at the ends of the electrode area prior to the application of the inner silver varnish coating. The wedge shaped annular grooves formed by the rings and the glass tube walls are filled with an insulating varnish 54. Contact may be made to the inner electrode by a spring clip 55.

Figure 7 illustrates a compensating auxiliary condenser 60 which may be connected in shunt with condenser 14 for temperature compensation if desired. Condenser 60 comprises a sheet metal electrode 61 clamped against the face of a ceramic

plate 62. The other condenser electrode 63 is formed of thermostatic bi-metal which is clamped on top of electrode 61 with a mica sheet 64 between them. Thermostatic electrode 63 is clamped only at one edge so that temperature variations will produce variations in spacing between the free edge of the electrode and the stationary electrode 61, thus varying the capacity.

Figures 8 and 9 illustrates a suitable form of spark gap 13. This comprises a pair of copper rods 70, each having a flange 71 near one of its ends and a recess in the end containing a tungsten rod the end of which form the active electrode surface of the spark gap. Copper rods 70 are clamped in suitable brackets 72 on a base plate 73 with the ends of tungsten electrodes 74 in opposed spaced relation. A sleeve 75 formed of a short length of Koroseal tubing or similar material is forced over the flanges 71 on the copper rods to thereby inclose the spark gap area. A copper tube 76 is forced over the Koroseal tubing to prevent bulging of the Koroseal at high altitudes where the internal pressure will exceed atmospheric pressure. I have found that this spark gap construction will withstand large atmospheric changes in pressure and afford satisfactory operation under widely varying conditions.

Figures 10 and 11 illustrate the preferred construction for inductance coil 19. The coil is made up of a set of four universal wound coil sections 90 on a suitable coil form having a powdered iron core 91 and a powdered iron cup 92 forming a return path inclosing the coil sections. An eccentrically mounted core piece 93 is secured to the free end of core 91 and may be adjusted to vary the gap in the magnetic circuit. This permits accurate adjustment in the resonant frequency of the circuit.

Suitable values for the circuit elements can readily be chosen by those skilled in the art when an operating frequency is decided upon and the distributed capacitance and inductance of the system taken into account. Since the inductances 18 can be varied after assembly by adjusting pole segments 93, it is readily possible to arrive at the approximate values for the capacitances and inductances by computation and then make final adjustments after the system is assembled and tested. The other parts can also be adjusted or replaced until perfect resonance is achieved.

In one system a magneto delivering between 1,500 and 2,000 volts was used. Condenser 14 had a value of .00403 microfarad, inductance 18 a value of 75 millihenries. The circuit oscillated at 296 kilocycles. Inductance 18 and capacitance 18 were arranged as shown in Figure 2 and had values of 2.1 millihenries and 125 micro-microfarads, respectively.

While the present invention, as to its objects and advantages, has been described herein as carried out in specific embodiments thereof, it is not

desired to be limited thereby but it is intended to cover the invention broadly within the spirit and scope of the appended claims.

What is claimed is:

- 5 1. An ignition system for an internal combustion engine comprising a magneto, a tuned oscillatory spark gap circuit excited thereby, a current distribution circuit fed by said oscillatory circuit comprising a distributor and a plurality of individually tuned spark plug branch circuits tuned to the frequencies of said oscillatory spark gap circuit, each of said spark plug circuits including reactive resonant circuit elements and a spark plug connected between points of high resonant potential difference in said circuit.
- 10 2. An ignition system for an internal combustion engine comprising a low tension magneto, a high frequency tuned oscillatory spark gap circuit excited thereby, a low tension current distribution circuit fed by said oscillatory circuit comprising a distributor and a plurality of individual spark plug work circuits connected in sequence to said oscillatory circuit by said distributor, each of said spark plug circuits including resonant circuit elements, forming, when connected by said distributor to said oscillatory circuit, a branch circuit resonant at the frequency of said tuned oscillatory circuit, whereby a high oscillatory potential difference is developed across a pair of terminals in said spark plug circuit, and a spark plug having its electrodes connected to said terminals.
- 15 3. An ignition system for an internal combustion engine comprising a magneto, a spark gap connected across the output terminals thereof, a series arrangement of capacitance and inductance also connected across said terminals, and a current distribution circuit connected to a point located between said capacitance and at least part of said inductance, said distribution circuit comprising a distributor and a plurality of individual spark plug circuits connected to said point in sequence by said distributor, each of said spark plug circuits including a series arrangement of
- 20 45 capacitance element and inductance element and a spark plug connected to receive the oscillatory energy across one of said elements.
- 25 4. An ignition system for an internal combustion engine comprising a magneto, a spark gap connected across the output terminals thereof, a series arrangement of capacitance and inductance also connected across said terminals, and a current distribution circuit connected to a point located between said capacitance and at least part of said inductance, said distribution circuit comprising a distributor and a plurality of individual spark plug circuits connected to said point in sequence by said distributor, each of said spark plug circuits including a series arrangement of
- 30 45 capacitance element and inductance element and a spark plug connected across one of said elements.
- 35 5. An ignition system for an internal combustion engine comprising a magneto, a spark gap connected across the output terminals thereof, a series arrangement of capacitance and inductance also connected across said terminals, and a current distribution circuit connected to a point located between said capacitance and at least part of said inductance, said distribution circuit comprising a distributor and a plurality of individual spark plug circuits connected to said point in sequence by said distributor, each of said spark plug circuits including a series arrangement of
- 40 45 capacitance element and inductance element and a spark plug connected to receive the oscillatory energy across one of said elements.
- 45 6. An ignition system for an internal combustion engine comprising a magneto, a spark gap connected across the output terminals thereof, a series arrangement of capacitance and inductance also connected across said terminals, and a current distribution circuit connected to a point located between said capacitance and at least part of said inductance, said distribution circuit comprising a distributor and a plurality of individual spark plug circuits connected to said point in sequence by said distributor, each of said spark plug circuits including a series arrangement of
- 50 45 capacitance element and inductance element and a spark plug connected across one of said elements.
- 55 7. An ignition system for an internal combustion engine comprising a magneto, a spark gap connected across the output terminals thereof, a series arrangement of capacitance and inductance also connected across said terminals, and a current distribution circuit connected to a point located between said capacitance and at least part of said inductance, said distribution circuit comprising a distributor and a plurality of individual spark plug circuits connected to said point in sequence by said distributor, each of said spark plug circuits including a series arrangement of
- 60 45 capacitance element and inductance element and a spark plug connected across one of said elements.
